WINDING MACHINE

Winthrop L. Perry, Milford, N. H., assignor to Abbott Machine Co., Inc., Wilton, N. H., a corporation of New Hampshire

Application April 17, 1956, Serial No. 578,756

4 Claims. (Cl. 242—31)

This invention relates to winding machines, particularly for winding bobbins with the so-called filling or weft wind, as for use in loom shuttles. In that type of wind the thread is traversed with a relatively short stroke and the zone of this short stroke of traverse is progressively advanced along the winding bobbin.

In this type of machine, particularly when fully automatic, it is desirable to impart the short stroke of traverse by means of a friction slider, that is, a slider which has only a frictional engagement and not a positive engagement with a reciprocating traverse rod. Rotating cams or cam-like elements are almost universally used to effect the short stroke traversing motion in filling winding. The use of a reciprocating traverse rod enables the driving cam to be well out of the way of the region of winding and avoids any need for this cam to follow along with the slow axial progression of the traverse. The frictional connection between the slider and traverse rod enables the slider, and thread guide to be readily slid back to a position where the winding is to start on the next bobbin. The frictional connection between the slider and traverse rod also facilitates winding the starting bunch of thread on a loom bobbin, since the frictional connection permits the thread guide to be confined to a narrow zone during the winding of the bunch, while the traverse rod is making its regular traversing stroke which is longer than the length of the narrow zone of bunch winding.

Although a friction slider has these advantages, it has also imposed a limit upon the speed of winding, and the present invention aims to overcome this.

The friction slider principle involves a sufficient grip of the slider upon the reciprocating traverse rod so that the slider will follow fairly closely the motion of the traverse rod. Thus after each stroke, the friction slider, under the driving influence of the rod, needs to be accelerated to the relatively high speed of traverse. If the grip of the slider upon the rod is insufficient, there is lost motion between the rod and slider during the times the slider should be moving the thread in accordance with the movement of the rod, and the movements of the slider and thread become erratic. In practice, in the use of friction sliders such as disclosed in U. S. Patents Nos. 2,362,455 and 2,377,367, it has been customary to arrange the slider to grip the rod with a frictional grip of 2 to 2 1/4 pounds, to cause the slider properly to partake of the motion of the rod.

However, it can be demonstrated that this required grip rises disproportionately if the speed of the rod is increased. It is believed that the force required to accelerate the slider from a standstill increases as the square of the speed to which it is accelerated. This increased force could of course be obtained from the reciprocating rod, but for transmission of this increased force from the rod to the slider, correspondingly greater frictional grip of the slider upon the rod would be needed, so that the required frictional grip likewise would increase as the square of the speed. Thus doubling the speed would require four times the frictional grip, tripling the speed

2

would require nine times the frictional grip, etc. For instance, if two pounds frictional grip are required for operation at a given speed, tripling the speed of the device would require a frictional grip in the region of eighteen pounds.

Such strong frictional grip of the slider on the rod would cause undue wear and strain during the progressive advance of the slider along the rod during winding. After the bobbin was wound the excessive grip of the slider upon the rod would interfere with sliding the slider back along the rod.

It can now be seen that by its peculiar requirement that the slider should follow closely the movement of the rod and yet be readily slidable along the rod, the friction slider principle has imposed a limitation on the speed of traverse, and hence on the speed of winding.

The present invention provides a very easy-running machine, in which strain and wear are kept at a minimum even for very high speeds of traverse.

20 By way of explanation of the present invention, the friction slider principle can be adapted to very high speed winding by relatively simple changes along the following lines. The frequency of reciprocation (strokes per minute) of the traverse rod and accordingly of the friction slider are increased to correspond to the desired high frequency of traverse and high speed of winding, but by reduction in the length of stroke of the traverse rod and friction slider their linear velocities are kept moderate. The relatively short stroke of the slider is converted to a longer stroke of traverse by means of the thread guide arm which traverses the thread. The moderate linear speed of the traverse rod and slider permits the slider to grip the rod only lightly, and yet partake properly of the motion of the rod during winding at high speed. 35 No excessive force is required either for the progressive advance of the slider along the rod during the winding operation or for the return of the slider along the rod in preparation for the next winding operation.

Various types of winders have of course been provided 40 with pivoted thread guide arms, but so far as I am aware, these have not served the purpose of reducing the grip which a friction slider needs to exert upon its traverse rod in order to follow properly the motion of the rod. The invention is applicable to automatic loom bobbin 45 winders, whether their winding units travel or are stationary.

In the accompanying drawings,

Fig. 1 is a plan view of the head portion of a traveling spindle winding unit including the improved traverse 50 mechanism of the present invention;

Fig. 2 is an elevation of the device of Fig. 1;

Figs. 3 and 4 are plan views on a larger scale than Fig. 1, showing the thread guide carriage, these views showing the thread guide carriage in opposite extreme positions;

Fig. 5 is a vertical sectional view taken on the line 5—5 of Fig. 3;

Fig. 6 is a view taken on the line 6—6 of Fig. 5; and

Fig. 7 is an enlarged view of the friction element, carried by the slider, frictionally gripping the traverse rod.

The winding unit to which the invention is shown as applied includes an inner chuck 20 for the base of the winding bobbin and an outer retractable chuck 21 for the tip of the winding bobbin. Inner chuck 20 is driven 65 by a direct connection from an electric motor 25 which also, through a worm, worm gear, traverse cam and cam follower, reciprocate the traverse rod 30. These driving connections are similar to those of said U. S. patents. It may be pointed out however that the stroke 70 of the traverse rod of the present device, is for example, only one third that of the stroke of the traverse rod in the winding unit of said patents, and that in use, the

motor 25 of the present device may have a speed of for example three times that of the motors of the winding units of said patents. This increase in motor speed, and corresponding increase in speed of winding, may most readily be obtained by an increase in the frequency of the supply current, for example from sixty cycles to one hundred eighty cycles.

The thread guide carriage indicated generally at 40, is movable along a bar 41 parallel with the axis of the winding bobbin. Any suitable means may be provided for imparting a progressive advance to the thread guide carriage from the base to the tip of the bobbin, either under the control of a feeler which responds to the growth of the winding upon the bobbin, or at a predetermined rate. For simplicity, the thread guide carriage is here shown as provided with a connection for advancing it in this latter manner, that is, at a predetermined rate. A bar 43, slideable in guides 44 carries upstanding cam follower rolls 45, 46 and 47, and is interconnected by a bracket 48 with the thread guide carriage as shown in Fig. 2. Cam follower rolls 45, 46 and 47 are adapted to engage successive stationary cams C along the course of the travel of the winding unit, to advance the thread guide carriage from the base to the tip of the bobbin. Other stationary cams may engage the rollers to move the thread guide carriage back toward the base chuck preparatory to reception of a new empty bobbin in the chucks. A friction slider indicated generally at 50 in Figs. 3 to 5 includes the general constructional features of the friction slider of said patents. In particular the slider includes end plates 51, 52 through which the traverse rod 30 loosely passes, a top plate 53 and a bottom plate 54, these four plates being riveted together into the form of a rigid box-like structure.

Within this box-like structure a sheet of felt 56 is held wrapped around the traverse rod 30, in frictional engagement therewith, by a metallic spring clip 57.

The friction slider thus grips the traverse rod frictionally, and as indicated above, the grip may be in the region of two pounds, which is a sufficiently light grip to enable the slider to be slid along the traverse rod easily.

As shown in Figs. 3 and 5 a portion 53^a projecting from the top plate 53 of the friction slider extends into a groove in the thread guide carriage, this portion 53^a carrying anti-friction pads 58 which slide in the groove, guiding the slider and preventing rotation around the traverse rod.

A plate 60, secured to the thread guide carriage 40, has upstanding portions 61 and 62 which limit the motion of the friction slider relative to the thread guide carriage. As shown, this motion is relatively short, only approximately one-third of the stroke required for the thread guiding end of the thread guide. The reciprocating motion of the traverse rod 30 is correspondingly short, being approximately the same in length as the length of the relative motion between the friction slider and the thread guide carriage.

The thread guide is in the form of an arm 65 having any suitable thread engaging member such as an eye 66 at its outer end which overlies the winding bobbin. The thread guide arm is under the joint control of the thread guide carriage and friction slider and is so engaged by these that although the thread is traversed at a high speed at the point 66, this high speed is derived from movement of the friction slider which is materially slower, for example only one-third as fast as the speed of traverse of the thread. This relation of speeds is obtained by reason of the fact that the distance between the places of operative engagement of the arm by the slider and by the carriage is materially less than the distance between this latter place and the region of traverse of the thread by the eye 66. A moderate speed of the friction slider relative to the carriage thus produces a much higher speed of traverse of the thread, for example a speed of traverse appropriate to operating

the motor 25 with 180 cycle current instead of 60 cycle current, with corresponding increase in speed of winding.

In the preferred embodiment shown, the thread guide is carried at its inner end by a post 70 which pivots in the thread guide carriage 40. Then at about one-third the distance from this pivot point 70 to the point 66, the thread guide extends slidably through a sleeve 71 of anti-friction material pivoted at 72 to the friction slider. Other specific forms of interconnection of the thread guide arm, thread guide carriage and friction slider, having a similar motion-multiplying effect can be employed, the arrangement here shown being preferred because of its simplicity, compactness and lightness.

It will now be apparent that the invention has removed the limitation previously inherent in traversing mechanism of the friction slider type, namely the limit upon winding speed that has been imposed by necessity for excessively high gripping force of the slider upon the traverse rod. By use of the present invention, the gripping force can be light, permitting easy operation of the device in the shifting of the slider from base to tip of the bobbin during winding, in the return of the slider in preparation for start of winding, and during confinement or restraint of the slider to a restricted zone during bunch winding.

In the preferred form of friction slider shown, a post 75 extends up from the top plate 53. This post may be engaged by any suitable member to adjust the slider from its position of Fig. 4 to its position of Fig. 3 after the carriage 40 has been returned to a position near the base chuck 20. When embodied in a machine in which the winding units travel, such member may be interposed in the path of the post and exert a camming action thereon. The post 75 may also be utilized to restrict the slider from taking its full length of stroke during winding of the starting bunch, in a manner similar to the roller numbered one hundred sixty-five shown in Fig. 26 of said Patent No. 2,377,367.

I claim:

40. 1. Winding machine traverse mechanism comprising a thread guide carriage adapted for progressive advance along the winding bobbin, a reciprocating traverse rod, a slider frictionally gripping the traverse rod and reciprocable thereby, a thread guide arm adapted to traverse the winding thread, said arm being operatively connected to the carriage and to the slider and controlled jointly by the carriage and slider, the distance between the places of operative connection of the arm to the slider and to the carriage being materially less than the distance between this latter place and the region of traverse of the thread by the arm, so that the linear movements of the frictionally driven slider are materially shorter and slower than the corresponding traversing movements of the thread, whereby notwithstanding high speeds of traverse of the thread the slider need grip the traverse rod only lightly.

45. 2. Winding machine traverse mechanism as claimed in claim 1 in which the thread guide arm is operatively connected to the slider between the region of traverse of the thread and the place of operative connection of the arm to the carriage.

50. 3. Winding machine traverse mechanism comprising a thread guide carriage adapted for progressive advance along the winding bobbin, a reciprocating traverse rod, a slider frictionally gripping the traverse rod and reciprocable thereby, a thread guide arm adapted to traverse the winding thread, said arm being pivoted to the carriage and operatively connected to the slider and controlled jointly by the carriage and slider, the distance between the place of operative connection of the arm to the slider and the point of pivoting of the arm to the carriage being materially less than the distance between this point of pivoting and the region of traverse of the thread by the arm, so that the linear movements of the frictionally driven slider are materially shorter and slower than the corresponding traversing movements of the thread, where-

by notwithstanding high speeds of traverse of the thread the slider need grip the traverse rod only lightly.

4. Winding machine traverse mechanism as claimed in claim 3 in which a sleeve pivoted to the slider operatively connects the slider to the thread guide arm, the 5 arm being slidable in the sleeve.
